UNITED STATES PATENT OFFICE.

CHARLES F. MORGAN, OF JACKSON, TENNESSEE.

WINDOW FOR FREIGHT BOX CARS.

Application filed October 6, 1924. Serial No. 741,953.

To all whom it may concern:

Be it known that I, CHARLES F. MORGAN, a citizen of the United States, residing at Jackson, in the county of Madison and State of Tennessee, have invented certain new and useful Improvements in Windows for Freight Box Cars, of which the following is a specification.

This invention relates to windows for freight box cars. Freight box cars are now very generally provided with windows which are mounted upon the outer side of the car at the end of the same and frequently are detached during travel of the car so that they fall upon the track rails and cause derailments, resulting in damage to property and frequently in loss of life. It is also necessary to secure cleats around the sides or edges of such windows to protect the contents of the car from the effects of weather and fire and also necessary to seal the windows, and records must be made of the seals at the various stopping places of the cars. My invention seeks to provide a window which will effectually protect the contents of the car against the effects of weather or fire yet will provide for ventilation of the car when necessary. The invention also seeks to provide a window which will be securely held in place and which cannot drop upon the track rails to cause derailments. Other objects and advantages of the invention will hereinafter appear, and the invention resides in certain novel features which will be hereinafter first fully described and then more particularly pointed out in the appended claims.

In the accompanying drawings:

Figure 1 is an elevation of a portion of the end of a box car showing my improved window applied thereto;

Fig. 2 is a similar view of the inner side of the car;

Fig. 3 is a view similar to Fig. 2 but showing the window arranged to permit ventilation of the car, and

Fig. 4 is a vertical section on the line 4—4 of Fig. 2.

The car body 1 is of any preferred form and is provided with a window opening 2 in its end. A solid window or closure 3 is provided of such form and dimensions that it may fit closely within the window opening, and this window is secured to the car body by hinges 4 secured to an end of the window and to the inner side of the car

body so that, when the window is open, it will swing against the inner side of the car body. To hold the window in closed position, a bolt or other fastening 5 is provided at that edge thereof which is opposite the hinged edge and is adapted to engage a socket provided therefor in the body of the car, as will be readily understood. Merely as a matter of convenience, I prefer to arrange the hinges at the lower edge of the window, as clearly shown in the drawings, but it will be understood that the hinges may be arranged at the side of the window so that the latter will swing laterally instead of vertically if preferred. To further secure the window in its closed position and effectually prevent its opening from the outer side of the car, a bar 6 is disposed across the window and has its ends removably engaged in eyes or other bearings 7 secured upon the car body at the sides of the window opening, as shown and as will be readily understood. Upon the outer side of the car body around the window opening, I secure the weather strips 8 which project over the window opening, as shown most clearly in Fig. 4, whereby the window, when in closed position, will abut against the inner side of the weather strip. The closing movement of the window is thus limited so that the window cannot be swung to a position in which it will project beyond the side of the car and the parts are so proportioned that, when the bolt 5 is in locking position and the bar 6 in place, the window will be held closely against the weather strip and the entrance of water to the car will be thus prevented. To shed rain and other forms of moisture, a strip 9 having its upper edge beveled or convex is provided immediately adjacent and abutting the upper edge of the lower member of the weather stripping frame 8, as shown in Fig. 4.

A ventilating window frame 10 which may be of any convenient or preferred construction is provided, and this frame is secured by hinges 11 to the inner side of the car body at that side of the window opening remote from the hinges 4. While the present illustration shows this ventilating frame as arranged above the window opening, it will be understood, of course, that it may be arranged at one side of the same without involving any departure from my invention. A bolt or other fastening 12 is mounted upon the inner side of the car body immediately

below the window opening to engage the free end of the ventilating frame when it is lowered position, as shown in Fig. 3, and when the ventilating frame is in raised position, as shown in Figs. 2 and 4, it will be held in such position by a latch 13, as will be readily understood. To provide further security for the contents of the car, it may sometimes be desirable to lower the ventilating frame, while the solid window is in its raised closed position in which event the securing bar 6 will be so shaped that it will pass over and across the ventilating frame, thus providing a very secure closure for the window opening which will make it exceedingly difficult to enter the car from the outside and withdraw the freight.

From the foregoing description, taken in connection with the accompanying drawings, it will be seen that I have provided an exceedingly simple window construction whereby the contents of the car will be protected against the weather and possible fire and the window cannot drop onto the rails to cause derailment of the car and possibly loss of life. Inasmuch as the window is arranged to open inwardly, it is not necessary to secure cleats upon the outer side of the car body to hold the window in place and the cost of labor and material involved in thus securing the window is eliminated. It will also be seen that, inasmuch as the window cannot be opened from the outer side of the car, the use of seals is not necessary and the cost of the seals is saved and the users of the car are not subjected to the expense of making records of the seal. In-

asmuch as the making of such records is eliminated, there is no liability to personal injury due to operatives climbing over drawheads to make the records and examine the seals. Inasmuch as the window cannot fall outwardly from the car, there is no chance of the train crew or other persons being injured from falling windows and the window opening is so effectually closed that the loss of freight by theft is prevented.

Having thus described the invention, I claim:

1. The combination of a car body having a window opening through its wall, an imperforate closure adapted to free said opening hinged upon the inner side of the car body wall at one side of the opening, and a ventilating frame adapted to free the window opening and hinged upon the inner side of the car body wall at the side of the window opening opposite the side of the opening at which the imperforate closure is hinged.

2. The combination with a car body having a window opening therein, of an imperforate closure hinged upon the inner side of the car body at one side of the window opening, means for securing the said closure in closed position, a ventilating frame hinged upon the inner side of the car body at the opposite side of the window opening, means for securing said ventilating frame in open position, and means for securing the same in closed position.

In testimony whereof I affix my signature.

CHARLES F. MORGAN. [L. s.]
